CLAIM

The ornamental design for an RV fridge fan, as shown and described.

DESCRIPTION

FIG. 1 is an isometric view of an RV fridge fan in accordance with the present application;
FIG. 2 is a left side view of the RV fridge fan;
FIG. 3 is a right-side view of the RV fridge fan;
FIG. 4 is a front view of the RV fridge fan;
FIG. 5 is a back view of the RV fridge fan;
FIG. 6 is a top view of the RV fridge fan; and,
FIG. 7 is a bottom view of the RV fridge fan.

1 Claim, 4 Drawing Sheets
